UNITED STATES PATENT OFFICE.

JAMES EDGAR LEE, OF CHICAGO, ILLINOIS.

THROW-OFF FOR PRINTING-PRESSES.

SPECIFICATION forming part of Letters Patent No. 586,981, dated July 20, 1897.

Application filed June 27, 1896. Serial No. 597,137. (No model.)

To all whom it may concern:

Be it known that I, JAMES EDGAR LEE, a citizen of the United States, residing at Chicago, in the county of Cook and State of Illinois, have invented certain new and useful Improvements in Throw-Offs for Printing-Presses, of which the following is a full, clear, and exact specification.

This invention relates to throw-offs for printing-presses to enable the pressman to prevent an impression at any time during the running of the press, and it is more particularly designed as an improvement upon devices of this character in which the back shaft or eccentric-shaft, usually journaled in the back legs, is actuated to change the stroke of the back legs through the instrumentality of a rod pivoted at one end to a crank formed on or secured to the eccentric-shaft and having its other end connected with some means of operation, such as an ordinary hand-lever.

In order to render the device precise and accurate in operation, mechanism of some kind is necessary to limit the throw of the actuating-lever and lock the parts in the position in which they have been set. Ordinarily the parts are so constructed as to lock when the impression is thrown on and thus insure against "working off;" but practice has demonstrated that it is equally important that the mechanism should be so locked also in its thrown-off position to prevent it from "working on." With devices of this character it has also been found in practice that the oscillation of the back legs imparts a to-and-fro rotary or oscillatory movement to the back shaft or eccentric-shaft by reason of the rod to which the crank on the back shaft is connected having a different center at its lower end from the center on which the back legs are pivoted. This motion of the back shaft or eccentric-shaft, though slight at each stroke of the back legs, nevertheless wears away the bearings of the back shaft to a material extent in a very short while and thereby renders the parts loose and seriously impairs the efficiency of the press.

One of the objects of my invention, therefore, is to provide improved means for causing the parts to become automatically locked in either position in which they may have been set or thrown.

Another object of my invention is to provide improved and simple mechanism for shifting the eccentric-shaft or back shaft 55 when it is desired to throw the impression on or off and at the same time avoid any independent rotary movement of the eccentric-shaft or back shaft during the operation of the press with the impression either on or off. 60

With these ends in view my invention consists in certain features of novelty in the construction, combination, and arrangement of parts by which the said objects and certain other objects hereinafter appearing are accomplished, all as fully described with reference to the accompanying drawings, and more particularly pointed out in the claims.

In the said drawings, Figure 1 is a side elevation of a portion of a printing-press provided with my improved throw-off, the back legs being shown at the extremity of their forward movement in dotted lines and the impression being "on." Fig. 2 is a similar view showing the impression thrown off. Fig. 3 is 75 a detail edge view of one of the connecting-rods hereinafter described; and Fig. 4 is a detail plan view of a bell-crank lever and connected parts pivoted to the frame of the press, the frame being shown in section. 80

In carrying out my invention the movable or vibrating part of the impression mechanism, usually the vibrating back legs, is provided with a shiftable connection with the operating mechanism of the press, such shiftable connection usually being in the form of the ordinary back shaft or eccentric-shaft, whereby the distance between the point of connection with such operating mechanism and said vibrating part or back legs may be 85 increased or diminished in order to prevent the form from coming against the platen when desired, and to this shiftable connection or back shaft is pivoted the upper end of an actuating-rod whose lower end is permanently 90 pivoted concentrically with the pivot of the back legs and yet shiftable lengthwise with reference to its own pivotal point, and to this rod is connected suitable automatically-locking mechanism for raising and lowering it 100 and thus shifting or partially rotating the back shaft or eccentric-shaft and throwing the impression on or off.

In the drawings, in which my invention is

shown as applied to that class of presses in which the platen is stationary, 1 represents the main frame; 2, the vibrating back legs; 3, the eccentric-shaft or back shaft, which is 5 journaled as usual in any suitable enlargement 4 on the back legs. 5 is the shaft or pivotal axis of the back legs, which may be journaled in the main frame 1, as usual, and 6 is the usual crank-disk, having wrist-pin 7, 10 connected by connecting-rod 8 with wrist-pin 9 of the eccentric-shaft or back shaft 3. All of these parts may be of the usual or any suitable construction.

The eccentric-shaft or back shaft 3 is provided with a side lug 10, which in effect is a crank-arm and to which is pivoted the upper end of an actuating-rod 11, whose lower end is pivoted concentrically with the axis or shaft 5 of the back legs 2 in such a manner 15 that the actuating-rod 11 may rise and fall for shifting the eccentric-shaft or back shaft 3. This pivotal attachment of the lower end of the actuating-rod 11 may be best accomplished by providing the same with a vertically-elongated passage or opening 12, which 20 embraces the outer end of the shaft 5, or, which would of course be the equivalent thereof, a lug or pivot-pin projecting from the frame 1 and being arranged concentrically 25 with the shaft 5. With this construction it will be seen that the back legs 2 and the actuating-rod 11 vibrate in unison, and the extent of their movement is precisely the same whether the impression be on or off, and consequently the shaft 3 is absolutely free from 30 independent movement or rotation, excepting at such times when it is shifted by the raising or lowering of the rod 11 for changing the impression, and hence the aforesaid objectionable continual independent oscillation of 35 the shaft 3, produced by the vibratory action of the back legs, is prevented.

The lower end of the actuating-rod 11 is provided with a boss 13, from the outer end 40 of which projects an upwardly-extending lip 14, which forms means for the pivotal connection of a link 15, whose upper end is pivoted to a lever 16, which in turn is secured by pivotal connection to the main frame 1 45 and is also pivotally connected at about its mid-length to the lower end of a link 18. The upper end of the link 18 is pivotally connected at 19 with the lower arm 20 of a bell-crank lever 21, whose other arm 22 is pivoted 50 at 23 to the lower end of a connecting-rod 24. The upper end of this connecting-rod 24 is pivotally attached at 25 to a hand operating-lever 26, which is pivotally supported at 27 upon the main frame or other suitable part 55 of the press. By this construction it will be seen that when the operating-lever 26 is pulled toward the pressman into the position shown in Fig. 1 the lower arm of the bell-crank 21 is raised from the position shown in 60 Fig. 2 to that shown in Fig. 1 and the actuating-rod 11 for the eccentric-shaft is also elevated and the impression thrown on by

reason of the larger side of the eccentric-shaft 3 being placed between the pivotal points 7 and 9, but the pivotal point of the lower end 70 of the rod 11 nevertheless remains concentric with the shaft 5 or pivotal point of the back legs 2, inasmuch as the end of the shaft 5, (or other lug concentric therewith,) projecting into the slot 12, does not change its position 75 with the rod 11.

The parts are so proportioned that when they are in the described thrown-on position the pivotal point 15^a of the link 15 will be concentric with the pivotal point of the rod 80 11, and consequently the oscillation of such rod 11 cannot impart any movement whatever to the link 15, and hence the vibratory action of the back legs cannot tend in the least degree to alter the position of the operating-lever 26, and therefore such lever will remain 85 in the position in which it is thrown and there will be no danger of the impression working off. In order, however, that the weight of the connections between the rod 11 90 and the lever 26 may not tend to depress the rod 11 and thus throw the impression off, some suitable means of automatically holding the connecting-rod 24 against downward movement may be provided. This means 95 preferably consists of a bend 28 in the connecting-rod 24, which carries the pivotal point 25 back of a straight line passing through the pivotal points 23 and 27, and consequently the weight of the rod 24 tends to lock the lever 26 against forward movement and absolutely prevents any downward pressure on the rod 11 from the connections at the lower end thereof.

When it is desired to throw the impression 105 off, the operating-lever 26 is shifted from the position shown in Fig. 1 to that shown in Fig. 2. This depresses the upper arm 22 of the bell-crank 21 and also depresses the lever 16, and in so doing carries the actuating-rod 11 110 downward to the position indicated in Fig. 2. When the parts are in this position and the impression is off, the pivotal point between the end of the lever 16 and the link 15 will be concentric with the pivotal point of the 115 rod 11 and back legs 2, and it will therefore be seen that the length of the link 15, or, in other words, the distance between the pivots at its ends, is equal to the throw of the rod 11, and this throw in the downward direction 120 is preferably limited by the upper end of the slot 12 coming against the protruding end of the shaft 5. Hence it will be seen that when the impression is off the vibratory action of the back legs 2 and the rod 11 cannot alter 125 the position of the lever 16 through the intermediary of the link 15, and therefore the impression will remain off until the operating-lever 26 is again thrown to the position shown in Fig. 1. This relative proportion of the 130 parts, which results in the described concentric location of the pivotal points, in itself is sufficient under ordinary circumstances to lock the parts against accidental movement

and prevent the impression from working on; but in order to further guard against the impression working on the bell-crank lever 21 is so proportioned that the pivot 21^a, which 5 connects it to the frame 1, will be in a straight line with the pivot which connects it to the upper end of the link 18 and that which connects the lower end of the link 18 with the lever 16, thus forming an absolute lock for 10 preventing the upward movement of the lever 16.

Having thus described my invention, what I claim as new therein, and desire to secure by Letters Patent, is—

15 1. A throw-off mechanism for printing-presses having in combination the operating mechanism of the press; the pivoted vibrating part of the impression mechanism having a shiftable connection with said operating 20 mechanism whereby the impression may be thrown on or off; a longitudinally-movable rod connected at one end to said shiftable connection for shifting it and having its other end confined to travel across the axis of the 25 pivot of said vibrating part whereby said axis will at all times pass through said rod, and means for moving said rod longitudinally, substantially as set forth.

2. A throw-off mechanism for printing- 30 presses having in combination the operating mechanism of the press; the pivoted vibrating part of the impression mechanism having a shiftable connection with said operating mechanism whereby the impression may be 35 thrown on or off; a pivot fixed concentrically with the center of vibration of said vibrating part of the impression mechanism; a longitudinally-movable rod connected at one end to said shiftable connection for shifting it and 40 having its other end provided with sliding connection with said fixed pivot, and means for moving said rod longitudinally adapted to lock the rod against longitudinal movement when the impression is thrown off, sub- 45 stantially as set forth.

3. A throw-off mechanism for printing- 50 presses having in combination the pivoted back legs, an eccentric carried by said back legs and having connection with some operating part of the press, a shiftable rod connected with said eccentric for rotating the same and having its end pivoted concentrically with the pivot of said back legs, and being longitudinally shiftable with relation to 55 its own pivotal point, a link pivoted to said rod and an operating-lever connected with said link, for raising and lowering said rod, substantially as set forth.

4. A throw-off mechanism for printing- 60 presses having in combination the pivoted back legs, an eccentric carried by said back legs and having connection with some operating part of the press, a shiftable rod for actuating said eccentric, having one end pivoted concentrically with the pivot of said back legs, a link pivoted to said rod and being substantially equal in length to the throw of said

rod, and means pivoted to said link for raising and lowering it and thereby shifting said rod, substantially as set forth.

70

5. A throw-off mechanism for printing-presses having in combination the pivoted back legs, an eccentric carried by said back legs and having connection with some operating part of the press, a rod connected with 75 said eccentric for actuating the same and having a slot, means engaging in said slot for pivoting said rod concentrically with the pivot of said back legs, and means for shifting said rod for throwing the impression on and off, substantially as set forth.

6. A throw-off mechanism for printing-presses having in combination the pivoted back legs, an eccentric carried by said back legs and having connection with some operating part of the press, a rod for actuating 85 said eccentric, having a slot; a pivot arranged concentrically with the pivot of said back legs and engaging in said slot; a link pivoted to said rod; a pivoted lever having one end pivoted to said link, and an operating-lever having jointed connection with said first lever, substantially as set forth.

7. A throw-off mechanism for printing-presses having in combination the pivoted 95 back legs; an eccentric carried by said back legs and having connection with some operating part of the press; a rod for actuating said eccentric, provided with a slot; a pivot arranged concentrically with the pivot of said back legs and engaging with said slot; a link pivoted to said rod at one end, a lever pivoted to said rod at the other end; the distance between the pivotal points at the opposite ends of said link being substantially equal to 100 the throw of said rod; and means for raising and lowering said lever, substantially as set forth.

8. A throw-off mechanism for printing- 105 presses having in combination the pivoted back legs; an eccentric carried by said back legs and having connection with some operating part of the press; a rod for actuating said eccentric, having a slot; a pivot arranged 110 concentrically with the pivot of said back legs and engaging in said slot; a link pivoted to said rod at one end; a lever pivoted to the other end of said link, the distance between 115 said pivots of said link being substantially equal to the throw of said rod; a pivoted bell-crank having one arm connected with said lever; and an operating-lever having connection with the other arm of said bell-crank, substantially as set forth.

9. A throw-off mechanism for printing- 125 presses having in combination the pivoted back legs; an eccentric carried by said back legs and having connection with some operating part of the press; a rod for actuating said eccentric, having a slot; a pivot arranged 130 concentrically with the pivot of said back legs and engaging in said slot; a link pivoted at one end to said rod; a lever pivoted to the other end of said link, the distance between

the pivots of said link being substantially equal to the throw of said rod; a pivoted bell-crank; a link connecting said lever with one arm of said bell-crank; an operating-lever, 5 and a rod connecting said operating-lever with the other end of said bell-crank, the parts being so proportioned that when the impression is thrown off the pivotal point at the upper end of the last said rod will be back of 10 a straight line passing through the pivotal point of said operating-lever and the pivotal connection of said bell-crank, substantially as set forth.

10. A throw-off mechanism for printing- 15 presses having in combination the pivoted back legs; an eccentric carried by said back legs and having connection with some operating part of the press; a rod for actuating said eccentric, having a slot; a pivot arranged 20 concentrically with the pivot of said back legs and engaging in said slot; a link 15 pivoted to said rod at one end; the lever 16 pivoted to the other end of said link, the distance be-

tween the pivots of said link being equal to the throw of said rod; the link 18 pivoted to 25 the lever 16; a bell-crank having one arm pivoted to said link 18; the rod 24 pivoted to the other arm of said bell-crank; the operating-lever 26 pivoted to said rod 24, and the 30 said parts being so proportioned that when they are in their thrown-off position the pivotal connection between the lever 26 and the rod 24 will be back of a straight line passing through the pivotal connection between the bell-crank and the rod 24 and the pivot of the 35 lever 26; and when in the thrown-on position the pivot of the bell-crank and the pivotal connection between the lever 16, link 18 and bell-crank will be in a substantially straight line; whereby the parts will be locked in 40 either position, substantially as set forth.

J. EDGAR LEE.
